UNITED STATES PATENT OFFICE

161,112

WHEEL CHAIR

William A. Linquist, Minneapolis, Minn.

Application January 19, 1950, Serial No. 7,317

Term of patent 14 years

(Cl. D15—1)

To all whom it may concern:

Be it known that I, William A. Linquist, a citizen of the United States, residing at Minneapolis, in the county of Hennepin and State of Minnesota, have invented a new, original, and ornamental Design for a Wheel Chair, of which the following is a specification, reference being had to the accompanying drawings, forming part thereof.

Referring to the drawings:

Fig. 1 is a view in perspective of a wheel chair, as seen from the front thereof, and incorporating my novel design; and

Fig. 2 is a perspective view of the wheel chair of Fig. 1, as seen from the side.

I claim:

The ornamental design for a wheel chair, as shown.

WILLIAM A. LINQUIST.
